CLAIM

The ornamental design for a pipette tip, as shown and described.

DESCRIPTION

FIG. 1 is a front view of a pipette tip that includes an internal filter;

FIG. 2 is a rear view thereof;

FIG. 3 is a side view thereof;

FIG. 4 is an opposing side view thereof;

FIG. 5 is an enlarged top view thereof;

FIG. 6 is an enlarged bottom view thereof;

FIG. 7 is a bottom perspective view thereof;

FIG. 8 is a top perspective view thereof;

FIG. 9 is an enlarged front, top perspective view thereof; and,

FIG. 10 is an enlarged rear, top perspective view thereof. The broken lines in the drawings depict portions of the pipette tip that form no part of the claimed design.
